UNITED STATES PATENT OFFICE.

KARL ORTH, OF DONAWITZ, NEAR LEOBEN, AUSTRIA-HUNGARY.

APPARATUS FOR CASTING PIG-IRON.

SPECIFICATION forming part of Letters Patent No. 714,818, dated December 2, 1902.

Application filed July 7, 1900. Serial No. 22,852. (No model.)

To all whom it may concern:

Be it known that I, KARL ORTH, a subject of the Emperor of Austria-Hungary, residing at Donawitz, near Leoben, in the Province 5 of Styria, in the Empire of Austria-Hungary, have invented certain new and useful Improvements in Apparatus for Casting Pig-Iron; and I do hereby declare the following to be a full, clear, and exact description of 10 the invention, such as will enable others skilled in the art to which it appertains to make and use the same, reference being had to the accompanying drawings, and to letters or figures of reference marked thereon, which 15 form a part of this specification.

This invention relates to improved apparatus for casting pig-iron which enables a large number of molds arranged in rows to be filled simultaneously with the molten pig metal and 20 also to be emptied in rows and the ingots distributed uniformly in the trucks for transporting the ingots to wherever required, the movements required for such filling and discharging being effected automatically and 25 regulated according to requirements from one and the same point.

The casting apparatus for this purpose consists of a distributing ladle or channel, into which the fluid pig metal is run directly from 30 the tapping-spout of the blast-furnace, such channel being arranged so as to be capable of being raised and lowered and also turned and being situated above a movable bed containing the rows of ingot-molds. These rows 35 of molds in being moved pass under the distributing-channel, so as to become filled therefrom, after which they are tilted over at a certain point, so as to have their solidified contents consecutively discharged into a movable chute, which delivers the ingots of pig metal into the trucks and in consequence of its motion distributes the same uniformly in the latter. On the return motion of the bed the rows of molds are consecutively raised 45 again and are brought back under the distributing-channel in proper position for receiving a fresh charge of pig metal.

The said casting and delivering apparatus is shown on the accompanying drawings, in 50 which—

Figure 1 shows diagrammatically the general arrangement of the casting apparatus,

while Fig. 2 is a section taken substantially on line C.D of Fig. 3, some of the parts being shown in elevation. Fig. 3 is a section substantially on the line A.B, Figs. 1 and 2. Fig. 4 is a section taken on lines I.K of Figs. 5 and 6. Fig. 5 is a section taken on lines G.H of Figs. 4 and 6. Fig. 6 is a plan of one of the ingot-molds. Fig. 7 is practically a side elevation of the temporary retaining devices of a set of molds; Fig. 8, an end view thereof, a section on lines E.F, Figs. 7 and 9; and Fig. 9 is a plan of Figs. 7 and 8. Fig. 10 is a side elevation, and Fig. 11 a plan, of the rack to 60 automatically dump and right the molds.

Attached to the tapping-spout *a* of the blast-furnace is a distributing ladle or channel *b*, provided with a number of spouts *10* and which is carried at one end on a spherical bearing *c*, while its other end carries a chain-wheel *11*, around which passes a pitch-chain *d*, from which that end of the channel is consequently suspended. By a suitable motion of this chain the channel *b* can be raised or 70 lowered and also turned for insuring a uniform distribution of the liquid pig-iron in the molds *f*, situated below it. These molds, which for facilitating the simultaneous casting of several ingots are divided by partitions *12*, are carried in rows on transverse bearers or 75 built-up girders *g*, which extend parallel with the channel *b* and are supported at their ends by means of trunnions *h* on traveling longitudinal bearers *i*, that form the side sills of 80 the carriage.

The transverse and longitudinal bearers constitute the traveling mold-bed, which can be moved to and fro by means of a rope *k*, passing over pulleys *j*, for bringing all the 90 rows of molds under the distributing-channel and within reach of the device for effecting the tipping over of the separate rows. This device consists of a bracket *l*, fixed at the side of one of the longitudinal bearers *i* and 95 having its upper surface formed as a toothed rack *13*, with which can come in contact toothed quadrants *m*, fixed on extensions of the trunnions *h*, situated on that side of the mold-rows. On moving the bed in the one 100 direction—*i. e.*, away from the distributing-channel—the toothed quadrants on coming into gear with the rack will be turned so as to effect the tilting of the respective mold-

rows, so as to dump or discharge their ingots. On moving the bed in the direction toward the distributing-channel the mold-rows are raised up again into the position for being filled, the molds of each following row being made to overlap those of the preceding row, so as to form a continuous closed surface. In order to produce this result, each mold *f* is provided on one side with a lip *14*, that overlaps the adjacent mold, effectually preventing metal from running between the rows of molds while the bed is passing under the distributing-ladle.

Below the bed is arranged the distributing-chute *n*, into which the cast ingots fall from the tilted mold-rows in order to be led by this onto the inclined plate *o* and thence into the trucks *p* to be loaded. The chute and inclined plate are fixed to bearers *q*, arranged parallel to the longitudinal bearers *i* of the mold-bed, which bearers *q* are supported by rollers *r*, which run upon rails *s*. The chute and the inclined plate are by this means capable of a longitudinal motion the extent of which is determined by the width of the truck, so that the ingots can be deposited in rows in the trucks, which are thus uniformly loaded without requiring manual labor for the purpose.

30 The shifting of the mold-bed and chute is advantageously effected by means of electromotors *t* and *u*, of which the one effects the rotation of the drum *v* through suitable speed-reducing gear, around which drum the rope *k* of the mold-bed is coiled, while the other electromotor effects the rotation, also through speed-reducing gear, of a shaft *w*, carrying toothed wheels gearing with toothed racks on the bearers *q* of the chute-frame. Both electromotors are started and controlled by an operative by means of suitable switch apparatus of known kind actuated near the tapping-hole of the furnace, which operative also effects the motion of the distributing-channel. In order that the mold-rows may be securely held in the upright position during the process of casting—*i. e.*, when they do not require to be tilted—there is provided, as shown at Figs. 7 to 9, on one of the trunnions *h*, a finger *x*, that is held by a spring-catch *y* and which in the upright position of the molds rests upon a cranked spring-arm *z*. When the molds are to be tilted, this finger, supported by the spring-pressure of the arm *z*, must first push the catch *y* to one side, after which the turning of the mold-row can take place. In like manner on the return motion the finger again pushes the catch to one side, after which the catch springs back over it and holds it in position.

65 The toothed rack on the bracket *l* can, if necessary, be arranged to be slid laterally out of gear with the toothed segment of the mold-rows in the event of the mold-bed requiring to be shifted when not casting on account of repairs, &c., as shown in Figs. 10 and 11, where the rack 13 is shown held lat-

erally adjustable on the bracket *l* by means of bolts 131, slidable in slots 132 in said bracket.

In order to enable the separate molds to be rapidly changed when necessary, they are secured to the transverse bearers by means of looped bolts and keys, as shown at Figs. 4 and 5.

The mode of working with the casting apparatus is as follows: The mold-bed is moved in the direction of the arrow, Fig. 1, underneath the distributing channel or ladle, and by a suitable adjustment and turning of the latter the previously-raised mold-rows are filled one after the other. As soon as the filling of the molds has been completed the electromotor *t* is reversed and the mold-bed is moved back. During this time the ingots will have cooled, and when the last-filled mold-row is brought with its toothed segment in gear with the toothed rack of bracket *l* it will in consequence of the continued motion of the bed be gradually tilted, so that the contents of the entire mold-row will fall onto the distributing-chute and will slide down the inclined plate into the trucks, situated close together. In a similar manner the other mold-rows will be consecutively tilted and emptied, the chute being at the same time moved to 95 and from by the second electromotor *u* in order to effect the uniform distribution of the ingots in the trucks, as above described. When all the mold-rows have been emptied, they are moved back toward the distributing-channel again and are at the same time raised into position for receiving a fresh charge.

I claim—

1. In a casting apparatus, a reciprocating bed, parallel rows of molds extending the width of the bed; in combination with a distributing-ladle extending across the bed and arranged to receive molten metal direct from a furnace and a number of pouring-spouts on said ladle corresponding to the number of molds in a row, substantially as described.

2. In a casting apparatus, a reciprocating bed, parallel rows of molds extending the width of the bed; in combination with a trough-shaped distributing-ladle extending across the bed and arranged to receive molten metal direct from a furnace, a number of pouring-spouts on said ladle corresponding to the number of molds in a row and means for tilting the ladle to pour metal simultaneously into all the molds of a row, substantially as described.

3. In combination, a blast-furnace, a moving casting-bed located beside said furnace, rows of molds carried by said bed, a distributing-ladle arranged to receive molten metal direct from said furnace, a number of pouring-spouts on one side of the ladle corresponding to the number of molds in a row, a bearing at one end of said ladle and means at the other for leveling and tilting the ladle, substantially as described.

4. In combination, a blast-furnace provided with a metal notch, a moving casting-bed lo-

cated beside the furnace, rows of molds carried by said bed, a distributing-ladle arranged to receive molten metal direct from the furnace, said ladle provided at one end with a 5 universal joint to a fixed element below the metal notch, a number of pouring-spouts on one side of the ladle corresponding to the number of molds in a row, a sprocket-wheel at the other end of the ladle and a chain in which 10 said wheel is hung, substantially as described.

5. In combination, a blast-furnace provided with a metal notch, a standard below the metal notch provided with a socket, a distributing-ladle suitably lined and arranged to receive 15 molten metal direct from the furnace, a trunnion on one end of the ladle and a ball thereon fitting said socket, a trunnion and sprocket-wheel at the other end, a number of pouring-spouts on the ladle, a chain in which the 20 sprocket-wheel and trunnion are hung and a casting-bed provided with parallel rows of molds reciprocal under the ladle, the number of molds in a row being the same as the number of pouring-spouts on the ladle, where- 25 by all the molds of a row can be simultaneously filled, substantially as described.

6. In combination, a distributing-ladle, a furnace arranged to discharge into the ladle, a number of pouring-spouts on the ladle and 30 a casting-bed reciprocal beneath the ladle, comprising a reciprocal carriage, rows of molds supported on trunnions on said carriage, there being as many molds in a row as there are pouring-spouts on the ladle, where- 35 by all the molds of a row will be simultaneously filled, substantially as described.

7. A casting apparatus comprising a distributing-ladle, a plurality of pouring-spouts on one side thereof, a casting-bed reciprocal 40 beneath the ladle, comprising a carriage, a plurality of rows of molds, each row mounted on trunnions and means located to dump each row of molds by the travel of the carriage in one direction and right said rows of molds by 45 the travel of the carriage in an opposite direction, substantially as described.

8. In a casting apparatus, a reciprocal casting-bed comprising rows of overlapping molds, girders supporting each row and 50 mounted on trunnions, a tilting distributing-ladle arranged above the bed positioned to receive molten metal direct from a furnace and pouring-spouts on the ladle, whereby all the molds of a row can be simultaneously filled during the passage of the bed beneath the ladle, substantially as described.

9. In a casting apparatus, a reciprocal bed comprising a carriage, rows of molds mounted on trunnions, lips on said molds on 60 one side arranged to overlap the adjoining side of one adjacent row of molds when in filling position and engage the bottom of the other adjacent row when in dumping position, substantially as described.

65 10. In a casting apparatus, a bed comprising a carriage formed of end and side sills, rows of molds mounted on trunnions held in

bearings on said side sills, said rows of molds having lips to overlap one adjoining row when in filling position and engage the up- 70 turned bottom of the other adjoining row, and means for dumping said rows by reason of the movement of the bed in one direction and righting them by reason of its movement in the other direction, substantially as de- 75 scribed.

11. In a casting apparatus, a bed comprising a carriage, parallel rows of molds provided with trunnions journaled on said carriage, each row of molds provided with lips that 80 overlap an edge of one of the adjacent rows when in filling position and engage the bottom of the other adjacent one when dumped, a sector for each row of molds, a rack fixed in the path of the sectors to dump and right 85 the rows of molds, substantially as described.

12. In a casting apparatus, a distributing-ladle, parallel rows of molds reciprocal thereunder, means for automatically dumping said molds at a predetermined point when they 90 are moved in one direction and right them when moved in the opposite direction, a trough arranged to receive the dumped castings and a device for delivering and loading them in regular order in suitable trucks, sub- 95 stantially as described.

13. In a casting apparatus, a distributing-ladle, parallel rows of molds mounted on trunnions on a reciprocal carriage, means at a definite point to automatically dump and 100 right the rows of molds, a truck independently reciprocal below the molds, a chute and a plate thereon, substantially as described.

14. In a casting apparatus, a reciprocal carriage, rows of molds mounted thereon, a 105 stop, a spring-catch and an arm for each row of molds, said arm arranged to strike said stop and be held by the catch, substantially as described.

15. In a casting apparatus, parallel built- 110 up girders, trunnions secured to each end, rows of molds keyed to each girder, a toothed sector and an arm on a trunnion of each girder, a stop against which said arms rest and a spring-catch to hold each arm against 115 its stop, substantially as described.

16. In a casting apparatus, a distributing-ladle positioned to receive molten metal direct from a furnace, rows of molds reciprocal 120 thereunder, the molds of a row adapted to be simultaneously filled from the ladle, means to automatically dump and right the rows of molds successively, a chute below the molds at the point where they are dumped, a reciprocal chute adapted to receive the ingots from the first-mentioned chute to regularly load them into cars, substantially as de- 125 scribed.

17. In a casting apparatus, a distributing-ladle positioned to receive molten metal direct from a furnace, a carriage reciprocal 130 below the ladle, rows of molds, each mold having a lip 14, a built-up girder to support each row of molds, trunnions on the ends of

the girders supported on the carriage, a toothed sector secured to a trunnion on each girder, a rack in the path of the sectors to dump and right the molds, a stationary chute 5 below the bed at the dumping-point and a reciprocable chute to receive ingots from the first-mentioned one to regularly load them, substantially as described.

In testimony that I claim the foregoing as my invention I have signed my name in presence of two subscribing witnesses.

KARL ORTH.
